Inventor
Ezra C. Pope
By R. C. A. Lacey
Attorney.

UNITED STATES PATENT OFFICE.

EZRA E. TOPE, OF LEESVILLE, OHIO.

GATE.

SPECIFICATION forming part of Letters Patent No. 296,648, dated April 8, 1884.

Application filed September 6, 1883. (Model.)

To all whom it may concern:

Be it known that I, EZRA E. TOPE, a citizen of the United States, residing at Leesville, in the county of Carroll and State of Ohio, have 5 invented certain new and useful Improvements in Gates; and I do declare the following to be a full, clear, and exact description of the invention, such as will enable others skilled in the art to which it appertains to 10 make and use the same, reference being had to the accompanying drawings, and to the letters and figures of reference marked thereon, which form a part of this specification.

My invention relates to improvements in 15 gates; and it consists in the construction, combination, and arrangement of the several parts hereinafter described and claimed.

In the drawings, Figure 1 is a front elevation of my gate. Fig. 2 is a detail view, showing the crane or supporting-frame; and Fig. 20 3 shows the latch devices in detail.

I have shown my gate mounted on a base, A, the hinge-post A being mounted on one end and the latch-post A² on the opposite 25 end of the same, as shown. The latch-post A² is provided on its inner face with one or more mortises, as shown in dotted lines, Fig. 1, to receive the extended ends of the gate-slats. The crane B is composed of the vertical bar B', the horizontal bar B², and the brace or strut B³. The bar B' is suitably hinged to the gate-post A', and the bar B² is provided 30 at its outer or swinging end with an extension or lug, B⁴, for the purpose presently described.

This lug B⁴ is secured on what, for convenience of reference, I call the "inner face" of the crane, and on its opposite or outer face, near its outer end, I secure a pin or stud, b. The gate proper is composed of suitable slats, C C, connected 35 at its swinging end by battens C', secured on opposite sides thereof. It also has a middle batten, C², and one, C³, secured at its inner end. The crane is provided on the post B', on the same side with the lug B⁴, with blocks B⁵, 40 which serve as means for connecting the hinges, and the gate is placed on the crane with one of its slats resting above these blocks and lug, and it is provided on its side with a roller, c, flanged at both ends and resting on the bar 45 B². This roller is arranged at about the middle portion of the gate, so that the same is

practically poised on the single roller, and may consequently be moved more easily back and forth in the operation of the device. I prefer to journal this roller in the small box- 55 ing c', secured to the gate-slat by bolts c² c³, arranged on opposite sides of and above the bolt c', on which the roller is journaled. The lever D is constructed at its lower end with the widened notch d, and has formed through 60 it the elongated opening or slot d', whereby the lever is secured on the bolt or shaft c⁴ of the roller, and is adapted to a limited endwise as well as to pivotal motion. The bolt c⁴ is provided with a shoulder or shield that ex- 65 tends from the bolt-head and passes into and through the slot d', and prevents the easy working of the lever D being interfered with by its being impinged upon by the roller c. A shoulder or hook, d², is formed on the side 70 of the lever next the bolt c², and somewhat above the slot d'. This hook or shoulder d² and the notch d in the end of the lever are arranged a distance apart equal to that between the pin or stud b on the crane and the bolt c² 75 on the gate when the latter is closed, and in such position of the gate the notch d rests on the pin b, and the hook or shoulder d² under the bolt c², and the slot d' permitting no endwise motion of the lever D, when the notch d 80 is pressed upon, the gate is locked against any longitudinal motion on the crane, and one or more of its slats being projected at its swinging end to enter the notches or mortises in post A', it is thereby prevented from any lateral motion. 85

To effect the unlocking of the gate, the lever is swung back, when the notch or shoulder escapes from under the bolt c², and the gate may be then easily pushed back and swung open. 90 When thus pushed back, the lug or extension B⁴ passes between the battens C', serving as a steady means as the gate is swung with the crane. As the gate is swung to and pushed on its roller toward the latch-post, the notch d 95 of lever D will engage on pin b, and as the motion is continued the lever will be automatically turned over, and the locking or latching of the gate accomplished. The weight of the lever above the shoulder d² will, with the endwise motion of the lever D, permitted by the slot d', be sufficient in a full-sized gate to hold 100

the said lever in the position shown in Fig. 1, whence it may be easily elevated to effect the unlatching, as hereinbefore described.

It is obvious that my construction might be modified without departing from my invention. For instance, the boxing might be dispensed with and the lever secured on a pivot independent of the supporting roller, and the shoulder or hook d^2 might be arranged to engage some other suitable bolt or projection than the bolt c^2 , and the notch at the base thereof might not be wider than necessary to engage the pin or stud; also, that the elongated opening might be replaced by an ordinary loose pivot-hole; but I prefer the construction as shown and described, as thereby a compact, simple arrangement is provided, and one securing an easy, smooth motion of the several parts.

20 Although I have shown my gate mounted on the base A, it is intended that in use the posts A' and A² be sunk into the ground sufficiently to retain their position, and thus to dispense with the base A.

25 It is obvious that the height of the gate from the ground may be altered by attaching the boxing c' and the mechanism it supports at a higher or lower point on the gate than that shown, and adjusting the gate on the crane B to correspond; and that, when desired, strands of wire may be substituted for a portion of the slats of the gate proper without interfering with its usefulness or ease of operation.

Having thus described my invention, what I claim, and desire to secure by Letters Patent, is—

30 1. The combination of a suitable crane or support provided with a stud or bearing-point, a gate placed on said crane, and provided also with a projection or bearing-point

above the bearing on the crane, and a lever pivotally secured on the gate, and adapted at its lower end to engage the bearing on the crane, and having formed on it a hook or shoulder arranged in position to engage the 45 bearing on the gate, all arranged and operating substantially as specified.

2. The farm-gate, substantially as described, composed of the gate, the crane hinged to the swing-post and supporting the gate, the pin 50 or stud secured on the crane, the boxing secured on the gate by bolts c^2 c^3 and incasing the roller, and the lever provided with widened end notch, d , adapted to engage the pin or stud on the crane, and having elongated opening d' , whereby it is pivoted on the roller-shaft, and constructed on its edge next the bolt c^2 with a hook or shoulder arranged to engage said bolt, all as and for the purposes specified.

3. The combination, with the crane having a stud or bearing, and the gate proper, of a lever pivotally secured to the gate, and adapted at its lower end to engage the stud on the crane, substantially as set forth.

4. The combination of the crane provided at its swinging end with a lug or projection, B¹, and having a stud or bearing-point, b, near said swinging end, the gate having end battens, C', and placed and movable on said crane, 70 the lever pivoted on the gate above the crane, and adapted at its lower end to engage the stud b, and suitable locking devices, substantially as specified.

In testimony whereof I affix my signature in presence of two witnesses.

EZRA E. TOPE.
